UNITED STATES PATENT OFFICE.

FREDERICK E. WILSON, OF BRADFORD, PENNSYLVANIA.

ANTISEPTIC SEWAGE-VAULT FOR CLOSETS.

1,079,970.

Specification of Letters Patent.

Patented Dec. 2, 1913.

Application filed November 18, 1912. Serial No. 732,034.

To all whom it may concern:

Be it known that I, FREDERICK E. WILSON, a citizen of the United States, residing at Bradford, in the county of McKean 5 and State of Pennsylvania, have invented certain new and useful Improvements in Antiseptic Sewage-Vaults for Closets, of which the following is a specification.

My invention relates to closets and has 10 particular reference to a closet system to be installed in houses, factories and schools having no water or sewage system.

The invention aims to provide a closet system of the above mentioned character, 15 which is comfortable and sanitary in use, and having novel means for disposing of human excrement in a most convenient and least objectionable manner.

An important object of this invention is 20 to provide agitator means for preventing the accumulation of the human excrement in any one portion of the collecting receptacle, or vault, whereby all of the excrement is uniformly subjected to the action of 25 chemicals contained in the vault and thoroughly disintegrated.

A further object of this invention is to provide novel connecting means between the bowl and dip-tube, whereby the human 30 excrement will be discharged into the central portion of the dip-tube and will not be caught upon the side walls thereof.

A further object of the invention is to provide a novel form of seal or gas trap 35 for the collecting tank or vault, which will satisfactorily prevent the gases in the vault from passing upwardly through the dip-tube, and at the same time not impairing the operation of the system as a whole.

40 A further object of my invention is to provide a novel connection between the dip-tube and vault, whereby the necessity of soldering these parts is dispensed with and the union obtained will not be effected by 45 changes in temperature, the frost, or slight relative movements between the parts.

A further object of this invention is to provide a dome upon the vault for holding an inlet ventilator, and rendering it possible 50 to entirely bury the vault, impossible for improper access to the vault, and proper access to the vault easy for the purpose of removing the residuum.

55 In the accompanying drawings forming a part of this specification and in which like numerals are employed to designate like

parts throughout the same. Figure 1 is a central vertical sectional view through the complete closet system, parts thereof being shown in section, and other parts broken away. Fig. 2 is a similar view, taken at a right angle to Fig. 1, showing a different form of means to operate the agitator in the vault; and, Fig. 3 is a detail elevation showing the bowl vent pipe connected with the vault vent pipe.

In the drawings, wherein for the purpose of illustration, I have shown a preferred embodiment of my invention, the numeral 4 designates the foundation or lower portion 70 of a dwelling or house, having a floor 5, as shown.

Mounted upon the floor 5 within the house, is a bowl 6, held against displacement by any suitable means. The lower 75 end of this bowl is formed open and discharges into a funnel or coupling 7, which in turn, discharges into a vertical discharge pipe or dip-tube, as shown. As far as I am aware, it has been customary to construct the upper end of the dip-tube 8 of 80 the same diameter as the lower end of the funnel 7. The adjacent parts were connected by any suitable means. It has been found that this construction is unsatisfactory, because the refuse or human excrement would be caught upon the side walls of the dip-tube, rendering the same foul and filthy.

My invention or improvement consists in increasing the diameter of the dip-tube, so 90 that the lower end of the funnel 7 will extend therein for a considerable distance, in spaced relation from the walls of the dip-tube, as shown. It is obvious that the funnel will now deliver the refuse into the central portion of the dip-tube, whereby the same will not be caught upon the side walls 95 of the dip-tube.

The vertical dip-tube 8 leads into one end of a sunken vault or collecting receptacle 9, as shown. Instead of soldering or otherwise rigidly connecting the lower end of the dip-tube with the vault, as has heretofore been customary, I provide the vault with an upstanding tube or sleeve 9^a, which is telescoped by the lower end of the dip-tube. When the parts are soldered, as above stated, it has been found that the connection will break, due to changes in temperature, the frost, or the slight relative movements 100 between the parts. By providing the tube or sleeve 9^a, for the purpose stated, this dis-

advantage is entirely overcome and a satisfactory union of the parts obtained, it being understood that the parts are free to slightly telescope each other. The vault or 5 collecting tank is preferably constructed of sheet metal, but other suitable material may just as well be employed, such as, wood, cement or the like. This vault has one end thereof extending under the foundation 4 and the vault is preferably entirely covered by earth, as shown. The vault may also be placed in the cellar.

Formed upon the closed upper end of the vault 9 is a dome or housing 10 of suitable 15 dimensions having its upper end normally closed by a vertically swinging lid or cover 11, as shown. This lid is hinged to the dome and may be securely locked in its closed position by any suitable means. The lid 11 is 20 provided with an opening to snugly receive the tubular body portion of an air inlet ventilator 12. This ventilator is rigidly secured to the lid 11 by soldering or the like. The lower end of the ventilator 12 passes 25 through the lower end 13 of the dome 10, as shown. By the provision of the dome 10, I am enabled to completely bury the vault 9 in the ground and to readily gain proper access to the interior of the vault or tank 9, 30 for removing, by pumping or otherwise, the residuum contained therein. When the lid 11 is locked in its closed position, children, animals, or the like cannot gain access to the vault. The vault is partially filled with a 35 chemical solution which deodorizes and disintegrates the refuse and toilet paper.

Connected with the upper wall of the vault 9 is a depending transverse plate or partition 9', having its lower end suitably spaced 40 from the bottom wall of the vault and extending into the chemical solution, as shown. This partition 9' divides the upper portion of the vault into chambers 9^a and 9^b, and thus forms a seal or gas trap, to prevent the 45 gases in the vault from passing upwardly through the dip-tube 8. Heretofore it has been customary to provide a seal or gas trap by extending the lower end of the dip-tube 8, so that the same passes into the vault or 50 tank 9 with its lower end submerged in the chemical solution. It has been found that 55 this construction gives a great deal of trouble. The space is so small at the lower end of the dip-tube that the small amount of chemical solution contained therein becomes so diluted in strength as to render it 60 unable to disintegrate and deodorize the refuse and toilet paper, whereby the dip-tube would become clogged. By my construction, I obtain a seal or gas trap, and at 65 the same time do away with the above stated disadvantages.

Connected with the central portion of the vault 9, outwardly of the partition 9', is a

vault strand or vent pipe 14, preferably vertically disposed and extending above the dwelling for a suitable distance, (not shown). The objectionable odors or gases from the vault 9 escape from the pipe 14, and in so doing create a draft or circulation upwardly 70 through the pipe 14 and into the vault through the inlet ventilator 12.

Permanently mounted upon the bowl 6 is a stationary seat 15, provided with the usual opening 16, adapted to register with an 75 opening 17, formed through a vertically swinging auxiliary seat 18. This auxiliary seat is hinged to the stationary seat 15, as shown at 19. Disposed within the upper portion of the bowl 6; near and below the 80 seat 15 and to one side of the opening 16, are horizontal rock-shafts 20 and 21, which have their outer ends journaled through suitable bearings, as shown. The inner ends of these rock-shafts carry cranks 22, which 85 are rigidly connected with a trap door or valve 23, serving to normally close the opening 16. The rock-shafts 20 and 21 are turned to bring the trap door to its closed position by a weight 24, disposed within the 90 bowl 6 and attached to a cable or chain 25, as shown. This cable is connected with a grooved pulley 26, which is mounted fast upon the rock-shaft 20. The rock-shaft 21 carries a pinion 27 at its outer end, which 95 engages a vertically movable rack 28, the upper end of which passes through an opening in the seat 15 and is engaged by the auxiliary seat 18. It is obvious that when the auxiliary seat 18 is depressed the trap 100 door 20 will be opened and when the auxiliary seat is released the weight will return the trap door to its closed position. Connected with one side of the bowl 6 is an air 105 inlet pipe 27', as shown. Connected with the seat 15 is a housing 28', having free communication with the interior of the bowl 6 and connected with a bowl vent pipe 29. This vent pipe preferably extends vertically above the top of the house for a suitable 110 distance (not shown). Instead of employing the long vertical pipe 29, I may dispense with the same and use a short vent pipe 30, shown in Fig. 3, which is connected with the vent pipe 14, as shown.

Mounted within the forward end of the vault 9, adjacent the bottom thereof and below the dip-tube 8, is a vertically swinging false bottom, agitator or deflector 31, which is retained in a vertically inclined 120 position, by means of a bracket or drop 31^a. The false bottom or plate 31 serves to deflect the refuse toward the outer end of the vault 9, upon the outer side of the partition 9', and the same is vertically movable to increase this deflecting power and to serve as an agitator. This agitator or false bottom 125 thus prevents the accumulation of the ref-

use in any one portion of the vault, particularly the portion of vault directly under the closet and dip-tube, so that the same will be properly acted upon by the chemical 5 solution. The lower end of the plate, false bottom or agitator 31 is pivotally connected with the bottom of the vault 9, by hinges 32 or the like. The false bottom 31 is swung vertically by a cable 33 or the like, which is 10 secured to the free end of the same. This cable extends upwardly through the dip-tube 8, into the bowl 6. At its free end the cable 33 carries a ring 35 or the like which is detachably mounted upon a hook, 35^a or 15 the like, disposed in the bowl 6 below the seat 15 and in convenient reach of the operator. By depressing the auxiliary seat 18, the trap door 23 will be opened, so that the operator may pass his hand through the 20 openings 16 and 17 to take hold of the ring 35 and draw the same upwardly through these openings to elevate or move the element 31.

In Fig. 2, the cable 33 is dispensed with 25 and a rod 36 used therefor, having connection at its lower end with a preferably horizontal plate or agitator 36^a. The rod 36 is pivotally connected at its upper end with the trap door 23. Instead of employing the 30 rod 36 I may use a chain or cable. It is thus seen that when the trap door 23 is moved the plate or agitator 36^a will be automatically raised and lowered.

It is to be understood that the form of 35 my invention herewith shown and described is to be taken as a preferred example of the same, and that certain changes in the shape, size and arrangement of parts may be resorted to without departing from the spirit 40 of the invention or the scope of the subjoined claims.

Having thus described my invention, I claim:

1. In apparatus of the character described, 45 a collecting tank, a transverse partition mounted within the tank and having its free end adapted to engage a chemical solution in the tank for forming a gas trap, a bowl discharging into the tank upon one 50 side of the partition, a pivoted false bottom normally resting upon the bottom portion of the tank, and means whereby the false bottom may be raised and lowered.

2. In apparatus of the character described, 55 a vault, a dip-tube leading into the same, a bowl connected with the dip-tube, a normally inclined agitator-plate disposed beneath the dip-plate, and means to raise

the agitator-plate to increase the inclination thereof.

3. In apparatus of the character described, 60 a vault, a dip-plate leading into one end thereof, a bowl connected with the dip-tube, and a transverse partition disposed within the upper portion of the vault at a considerable distance from the lower 65 end of the dip-tube for forming a chamber having a much greater cross-sectional area than the dip-tube, said transverse partition extending downwardly into a chemical so- 70 lution contained in the vault, as and for the purpose stated.

4. In apparatus of the character described, 75 a bowl, a vault disposed therebelow, means of communication between the bowl and vault, a vertically movable agitator disposed in the vault, and means to vertically move the agitator.

5. In apparatus of the character described, 80 a bowl, a vault, disposed therebelow, and in communication with the bowl, a pivoted agitator disposed in the vault to swing in a substantially vertical plane, and an operating element connected with the agitator and extending upwardly near the 85 top of the bowl.

6. In apparatus of the character described, 90 a bowl, a vault to receive refuse therefrom, a trap door mounted in the bowl, means to move the trap door, an agitator disposed in the vault, and operating connecting means between the trap door and agitator.

7. In apparatus of the character described, 95 a bowl, a vault to receive refuse therefrom, a movable seat mounted on the bowl, a trap door mounted in the bowl, operating connecting means between the movable seat and trap door whereby the latter is moved by the former, a movable agitator 100 disposed in the vault, and connecting means between the trap door and movable agitator.

8. In apparatus of the character described, 105 a collecting tank, a bowl, a conduit connected therewith and discharging into the collecting tank, a vertically inclined deflector disposed within the collecting tank below the conduit, means to support the deflector in its inclined position, and means to move the deflector.

In testimony whereof I affix my signature in presence of two witnesses.

FREDERICK E. WILSON.

Correction in Letters Patent No. 1,079,970.

It is hereby certified that in Letters Patent No. 1,079,970, granted December 2, 1918, upon the application of Frederick E. Wilson, of Bradford, Pennsylvania, for an improvement in "Antiseptic Sewage-Vaults for Closets," an error appears in the printed specification requiring correction as follows: Page 3, lines 58 and 62, for the compound word "dip-plate" read *dip-tube*; and that the said Letters Patent should be read with this correction therein that the same may conform to the record of the case in the Patent Office.

Signed and sealed this 23rd day of December, A. D., 1918.

[SEAL.]

J. T. NEWTON,

Acting Commissioner of Patents.
